SECTIONAL SHELVING

Hadwen C. Perry, Hyde Park, Mass.

Application November 23, 1942, Serial No. 466,575

6 Claims. (Cl. 211—148)

This invention relates to sectional shelving particularly designed for use in stores, stock-rooms and offices.

It is the general object of my invention to provide sectional shelving of an improved construction and in which the use of metal is almost entirely eliminated.

A further object is to provide sectional shelving of such a construction that the sections may be combined to fill any available or desired space, and to provide improved means for conveniently assembling adjacent sections and for firmly securing said sections to each other.

I also provide improved non-metal devices for removably securing the shelves in place, and I provide an improved and easily removable front piece for bins or other compartments which may be formed between the shelves.

My invention further relates to arrangements and combinations of parts which will be herein-after described and more particularly pointed out in the appended claims.

A preferred form of my invention is shown in the drawings, in which

Fig. 1 is a partial front elevation of my improved sectional shelving;

Fig. 2 is a partial sectional side elevation, taken along the line 2—2 in Fig. 1;

Fig. 3 is a partial perspective view of one of the upright members;

Fig. 4 is a partial perspective view of one of the shelves;

Fig. 5 is a similar view of a different type of shelf;

Fig. 6 is a detail sectional plan view, taken along the line 6—6 in Fig. 1;

Fig. 7 is a detail sectional front elevation, taken along the line 7—7 in Fig. 6;

Fig. 8 is a perspective view of a locking key to be described;

Fig. 9 is a partial front elevation, illustrating the manner of inserting a front piece in one of the bins or compartments;

Fig. 10 is a perspective view of one end of the front piece, looking substantially in the direction of the arrow 10 in Fig. 9; and

Fig. 11 is a partial perspective view of a back panel.

Referring to Figs. 1 and 2, one unit or section of my improved shelving comprises uprights 20 and 21, a bottom plate 22 and a top plate 23. The bottom plate 22 is transversely grooved at 25 to receive the lower end of the outer upright 20 and the top plate is similarly transversely grooved at 26 and 27 to receive the upper ends 50

of the uprights 20 and 21. Screws 28 or other suitable fastening means may be provided to hold the parts 20, 21, 22 and 23 in assembled relation.

5 The uprights 20 and 21 are transversely grooved, as indicated at 30, to loosely receive shelves 31 or 32. The shelves 32 (Figs. 1 and 5) are plain shelves and are used where the space or compartment above the shelf is not to be subdivided.

10 The shelves 31 are of greater thickness and are provided with transverse grooves 33 (Figs. 1 and 4) in their upper surfaces and with transverse grooves 34 of greater depth in their lower surfaces. The top plate 23 may be similarly provided with transverse grooves 35 corresponding in position to the grooves 33.

15 Any desired number of removable partitions 37 may be loosely inserted in selected pairs of grooves 33 and 35 to subdivide the compartment above a shelf 31.

20 In order to prevent forward displacement of the shelves 31 and 32, I provide the end upright 20 with a vertical groove 40 (Figs. 2 and 3) spaced 25 slightly rearwardly from the front edge of the upright, and I provide each shelf 31 or 32 with a vertical groove 41 (Figs. 4 and 5) at each end and correspondingly located, so that the grooves 40 and 41 jointly provide a continuous vertical 30 groove or passage. Similar grooves 40 are provided at each side of the intermediate uprights 21.

25 After the shelves have been inserted in the transverse grooves 30 between a pair of uprights, a pair of keys 44 (Figs. 7 and 8) are inserted in 35 the associated vertical grooves 40 and 41 and are held in vertical position by engagement of a lug or projection 45 at the upper end of each key with the upper surface of the shelf. After these keys are inserted, the shelf is securely held 40 from forward displacement and cannot be taken out until the keys have been previously removed.

35 The base plate 22 has a groove 50 (Fig. 2) in its upper surface and near its back edge, and the top plate 23 has a similar groove 51 in its lower surface. The end and intermediate uprights have corresponding vertical grooves 52 which complete a rectangular recess which loosely receives a back panel 55 as the parts are assembled.

45 If it is desired to partially close the front end of one or more compartments, I preferably provide a front piece 60 in the form shown in Figs. 9 and 10. At each end, the front piece 60 is reduced in thickness, as indicated at 61, to fit 50 loosely in the vertical grooves 40. These reduced

end portions 61 are notched as shown at 62 and 63 (Fig. 9) to clear the upper end of the keys 44.

The two end surfaces 65 of the body part of front piece 60 and the two end surfaces 66 of the projecting end portions 61 are all disposed in parallel planes and are inclined at a relatively small angle to the vertical, as clearly shown in Fig. 1. The included length of the front piece between the upper left-hand corner of the body part and the lower right-hand corner thereof is very slightly less than the distance between the uprights 20 and 21.

When the front piece 60 is in the position shown in Fig. 1, it is firmly held from outward displacement by the projecting end portions 61 which extend into the vertical grooves 40. When it is desired to remove one of the front pieces, this is easily done as indicated in Fig. 9.

For such removal, the left-hand end of the front piece 60 is lifted a short distance, so that the left end portion 61 is clear of the upright 20, after which the front piece may be swung forward and completely removed. The front piece may obviously be inserted with equal convenience by reversing the outlined procedure. I am thus able to insert or remove a front piece in any compartment and with the upper and lower surfaces of the compartment at a minimum spacing.

The manner of securing adjacent sections together is clearly shown in Fig. 1, where it will be seen that the bottom plate 22 has a reduced end portion 70 extending beyond the upright 21, and that the adjacent bottom plate 22^a has a reduced upper end portion 71 which extends only to the side of the upright 21. One or more screws 72 may be inserted downwardly to firmly secure the overlapping portions 70 and 71 to each other, with the portion 71 forming the second side of a transverse groove 25^a for the lower end of the intermediate upright 21.

Similarly the top plate 23 is extended and reduced in thickness as indicated at 75 in Fig. 1 and the adjacent top plate 23^a is correspondingly extended and reduced in thickness as indicated at 76. Screws 77 may be inserted downwardly through the parts 76 and 75 and into the upper end of the upright 21, thus firmly securing the adjacent sections together.

With the construction shown and described, sectional shelving of any desired width may be readily built up by assembling adjacent sections as previously described. Compartments of any desired height may be provided by inserting the shelves 31 or 32 in selected transverse grooves 30. Where it is desired to subdivide the compartments, grooved shelves 31 will be used, so that one or more partitions 37 may be inserted where desired. If it is desired to partially close certain compartments at the front end, front pieces 60 may be conveniently and easily placed in position.

It will thus appear that convenient sectional shelving has been provided, which is readily adapted to any desired purposes and in which no metal is used other than a few fastening screws or nails. All other parts of the shelving may be of wood or fibre or other suitable non-metallic sheet material.

Having thus described my invention and the advantages thereof, I do not wish to be limited to the details herein disclosed, otherwise than as set forth in the claims, but what I claim is:

1. Sectional shelving comprising top and bot-

tom plates, spaced uprights, means to secure said plates and uprights together, shelves removably mounted between said uprights, said plates being transversely grooved to receive said uprights and said uprights being transversely grooved to receive said shelves, said shelves and uprights having coacting recesses which are aligned when said shelves are in operative position, and removable locking devices insertable in said coacting recesses to prevent displacement of said shelves.

2. Sectional shelving comprising top and bottom plates, spaced uprights, means to secure said plates and uprights together, shelves removably mounted between said uprights, said plates being transversely grooved to receive said uprights and said uprights being transversely grooved to receive said shelves and said uprights and shelves being additionally grooved to jointly provide continuous vertical grooves spaced from the front edges of said parts, and locking keys insertable in said vertical grooves to removably secure said shelves in place.

3. Sectional shelving comprising top and bottom plates, spaced uprights, means to secure said plates and uprights together, shelves removably mounted between said uprights, said uprights and shelves being grooved to jointly provide continuous vertical grooves spaced from the front edges of said parts, and locking keys having projections formed at their upper ends, said keys being insertable in said vertical grooves to secure said shelves, and said projections overlying the associated shelves.

4. Shelving having compartments formed of horizontal elements retained between spaced uprights, said uprights having vertical grooves near their front edges, a front piece for a compartment having a body portion and having end portions of reduced thickness for insertion in said grooves, and all end faces of said body portion and end portions which engage abutting surfaces of said uprights being parallel and inclined to the vertical, whereby said front piece may be lifted at one end to remove said front piece from its compartment.

5. Sectional shelving comprising top and bottom plates, spaced uprights, means to secure said plates and uprights together, and means to mount spaced shelves between said uprights, one end portion of the bottom plate in one section being extended and reduced in thickness beyond one of the uprights and the end portion of the bottom plate of the next adjacent section being shortened and oppositely reduced in thickness to abut said upright and overlap said first reduced end portion, and fastening means downwardly insertable to secure said overlapping end portions together.

6. Sectional shelving comprising top and bottom plates, spaced uprights, means to secure said plates and uprights together, and means to mount spaced shelves between said uprights, one end portion of the top plate being grooved transversely to receive the upper end of the associated upright and being reduced in thickness above the associated upright, and the adjacent end portion of the top plate of the next adjacent section being oppositely reduced in thickness and overlapping said first reduced end portion, and fastening means downwardly insertable to hold said overlapping end portions together and also extending downward into the associated upright to secure both top plates to said upright.

HADWEN C. PERRY.
